DESIGN FOR A WEIGHING SCALE

Stan L. Hanssen, Chicago, Ill., assignor to Hanssen Scale Company, Chicago, Ill., a corporation of Illinois

Application June 25, 1936, Serial No. 63,483

Term of patent 14 years

To all whom it may concern:

Be it known that I, Stan L. Hanssen, a citizen of the United States, residing at Chicago, in the county of Cook and State of Illinois, have invented a new, original, and ornamental Design for a Weighing Scale, of which the following is a specification, reference being had to the accompanying drawing forming a part thereof,

The figure is a perspective view of a weighing scale showing my new design.

I claim:

The ornamental design for a weighing scale, as shown.

STAN L. HANSEN.
